UNITED STATES PATENT OFFICE.

RALPH W. PAYNE, OF IRVINGTON, NEW JERSEY, ASSIGNOR OF ONE-HALF TO VICTOR C. ARMSTRONG, OF HACKENSACK, NEW JERSEY.

WRENCH.

1,349,691.

Specification of Letters Patent. Patented Aug. 17, 1920.

Application filed March 17, 1916. Serial No. 84,962.

To all whom it may concern:

Be it known that I, RALPH W. PAYNE, a citizen of the United States, and a resident of Irvington, New Jersey, have invented 5 certain new and useful Improvements in Wrenches, of which the following is a specification.

The invention relates to ratchet wrenches, and more especially to wrenches especially 10 adapted for railway track work in screwing and unscrewing the nuts of rail joints. Objects and advantages of the invention will be set forth in part hereinafter and in part 15 will be obvious herefrom, such objects and advantages being attained and realized through the means and structures pointed out in the accompanying claim.

The invention consists in the novel parts, 20 articles, constructions, arrangements, combinations and improvements herein shown and described.

The accompanying drawings referred to herein, and constituting a part hereof, illustrate one embodiment of the invention, and 25 together with the description serve to explain the principles thereof.

Of the drawings:

Figure 1 is a plan view of a wrench constructed in accordance with the principles 30 of the invention;

Fig. 2 is a fragmentary view, on an enlarged scale, of the left hand end of Fig. 1;

Fig. 3 is a fragmentary section on the line 3—3 of Fig. 2;

Fig. 4 is a detail of the pawl, looking at the flat face thereof;

Fig. 5 is a detail of the pawl looking at Fig. 4 from the bottom;

Fig. 6 is a view similar to Fig. 2 but 40 showing a form adapted for very close work, that is where the nut is close to an angle or turn in the chair or the rail joint;

Fig. 7 is a fragmentary section on the line C—D of Fig. 6, and

Fig. 8 is a cross section through the head 45 with the socket members removed.

Referring by way of example to the accompanying drawings, a wrench is shown with a handle 1 and a head 2. The head 2 is preferably formed flat upon its sides and of general circular or annular form. The head 2 is provided with an internal circular aperture 3, and in accordance with certain features of the invention, the aperture 3 is 50 formed in the head 2 eccentrically to the

general circular shape of the head. This eccentricity of the aperture 3 in the head of the wrench is a distinctive and important feature of the invention inasmuch as it provides for arranging therein a rotating nut engaging unit whose center is arranged eccentric to the center of the supporting head on the longitudinal axial line of the tool, thereby disposing the nut engaging unit in such a position as to meet the space requirement 60 of the nuts on a rail joint. With the ordinary ratchet wrench in use it is frequently impossible to place the head of the wrench over a rail joint nut on account of the small space between the bottom of the rail joint 70 bar. Therefore, the present invention is intended to meet precisely that condition and to so locate the nut engaging unit at the extreme end of the tool opposite the handle so that such nut engaging member may pass 75 into the space between a rail joint nut and the foot flange of the joint bar and thus permit a workman to properly tighten the nut.

In connection with the modification shown in Figs. 6 and 7 of the drawings it is to be 80 observed that the nut members 5 and 6 project beyond the opposite faces of the tool head to provide nut receiving sockets, and the outer faces of said members taper from the head of the tool outwardly, the pitch of 85 said taper being substantially that of the inclined upper surface of the foot flange of a rail joint bar.

In accordance with one feature of the invention there is formed within the aperture 3, 90 and preferably centrally thereof, an inwardly projecting and preferably annular shouldered portion 4, the inward part of the aperture 3 being thereby rendered of less diameter. As shown, the inwardly projecting portion 4 has flat sides (see especially Figs. 2 and 8), and an internal circular or cylindrical bearing surface of less diameter than the aperture 3 at either side thereof. In the preferred form the aperture 3 opens 95 into the end of the head 2 (shown at the right in Figs. 2 and 3) but the inwardly projecting portion 4 forms a continuous ring past or across such opening in the end of the head 2. The internal cylindrical surface of the part 4 thus forms a supporting and bearing surface for the nut-engaging members 5 and 6, which rotate therewith while being supported and held in position 100 thereby.

Nut engaging members 5 and 6 are fitted into the aperture 3 in the head. In the preferred construction two such members are used, and are of like construction, and in such case a single description will suffice. The nut engaging member has ratchet teeth 7 arranged in annular series about its exterior periphery, the ratchet teeth fitting within the aperture 3 in the head. The nut engaging member has also an internal annular portion 8 of less diameter than the ratchet teeth bearing portion, the portion 8 fitting and rotating within the inwardly projecting shoulder part 4.

The inner faces 9 of the nut engaging members 5 and 6, according to certain features of the invention, are in contact within the shouldered portion 4 of the head. The nut engaging members are joined at said abutting faces 9 by torsion resisting devices projecting into the nut engaging members. The embodied form of said devices comprises dowels 10 fitting into corresponding holes in both the members 5 and 6. Screws 11 are also employed, passing in from the exterior, to also hold the nut engaging members from lateral displacement as well.

In the embodied form, a pawl is provided common to both sets of ratchet teeth on the respective nut engaging members 5 and 6. The pawl tooth proper comprises a broad member 12 working in a recess 13 extending transversely through the head 2. The tooth 12 at one end thereof engages the ratchet teeth 7 on the nut engaging member 5, and at the other end thereof it engages the ratchet teeth 7 upon the nut engaging member 6. At each of these parts the tooth is beveled as shown at 14, to reduce friction and to prevent a back drag on the nut during the idle or return movement of the wrench. Extending from the tooth 12 is a stem 15 working in an aperture 16 in the head 2, the pawl being spring-pressed by a suitable spring 17, encircling the stem 15 and being seated in an enlargement 18, at the outer part of the aperture 16.

There is thus provided an exceedingly rigid, compact and powerful construction, which is adapted to work in very close quarters. The twisting strain on the wrench, as well as the direct resistance of the nut, are adequately provided for in the arrangement of the ratchet teeth and pawl, and the coöperating parts, and by the dowels and screws connecting the nut engaging members.

In Fig. 7 of the drawings, the nut engaging members 5 and 6 are shown projecting outwardly from the head, and decreasingly beveled toward the outer end. In this form also, the inner portions of the

nut engaging members are made much stronger and heavier, by reason of the additional space available, the inner part of 65 each of the members 5 and 6 projecting radially inwardly, as shown at 20 in Figs. 6 and 7, giving a very heavy construction for the dowels and screws to hold in. In this form, the wrench will work in exceedingly close quarters, and while the strain of the nut is displaced from the center of the wrench, such strains are amply provided for by the features of construction already referred to and by the heavy construction for 75 the torsion resisting devices just described.

The flat sides of the ratchet teeth 7 on the members 5 and 6 which engage with the pawl in the preferred form, are cut slightly inwardly radially beyond the outer 80 periphery of the inwardly projecting parts 8 of the members 5 and 6, as appears best from Figs. 2 and 6. The parts 8 have grooves or recesses therein, and the central part 22 of the pawl tooth 12 is shaped to 85 engage the grooves and thus to provide an additional hold for the pawl all the way across, see also Figs. 4 and 5.

It will be understood from the foregoing that a construction has been provided realizing the objects of the invention and advantages herein set forth, together with other objects and advantages; and it will be further understood that departures may be made from the precise structure shown and 95 described, within the scope of the accompanying claim, without departing from the principles of the invention and without sacrificing its chief advantages.

What I claim as my invention and desire 100 to secure by Letters Patent is:—

A nut wrench of the class described comprising a handle carrying a head having an eccentric aperture and a rib within the same and lying in a plane between the opposite 105 faces of the head, and a rotatable ratchet nut-engaging unit journaled in said aperture and comprising duplicate members separably connected and having complementary teeth disposed in the same direction, 110 the tooth portions of the two members respectively lying on opposite sides of said rib, and said nut engaging unit having its center located on the longitudinal axis of the handle and between the center of said 115 head and one extreme end of the tool, and a pawl engaging said complementary teeth.

In testimony whereof I have signed my name to this specification in the presence of two subscribing witnesses.

RALPH W. PAYNE.
